APPARATUS FOR DEAERATING SIRUP

James Kantor, Chicago, Ill., assignor to The Liquid Carbonic Corporation, Chicago, Ill., a corporation of Delaware

Application March 2, 1938, Serial No. 193,419

1 Claim. (Cl. 183—2.5)

My invention relates to improvement in means for deaerating sirups used in the manufacture of carbonated beverages.

In the manufacture of carbonated beverages, usually a flavored syrup of a predetermined quantity is deposited in the bottle, after which the bottle is filled with carbonated water. The presence of air in the sirup causes numerous disadvantages. In the first place, one of the chief causes of spoilage of carbonated beverages is the presence of air in the sirup. Furthermore, the presence of air in the sirup causes a foaming or frothing of the sirup when it is initially deposited in the bottle and also causes a foaming or frothing of the contents of the bottle when the bottle is filled with carbonated water after the deposit of sirup therein. Such foaming or frothing seriously interferes with the filling of the bottle and with the proper operation of the machine in various ways.

It is one of the objects of my invention to, as far as possible, remove the air from the sirup prior to its delivery into the bottle.

For the purpose of disclosing my invention, I have illustrated an embodiment thereof in the accompanying drawing, in which,

The figure is a schematic view of an apparatus embodying my invention.

Referring to the figure, I have illustrated at 1 an ordinary siruper of the type which is now commercially used for depositing a measured quantity of sirup into the bottle. This siruper generally includes a rotatable tank adapted to contain the sirup which tank is provided with an annular well 2 having arranged therein the siruping stems or tubes 3. These siruping tubes have associated therewith the measuring cup 4 and a bottle bell 5, the arrangement being such that when the bell seats itself on the bottle, the stem 3 is projected into the bottle and the cup is raised to a position wherein a measured quantity of liquid contained therein will flow into the bottle. More detailed description of this structure is not believed to be necessary as the same is fully disclosed in the patent to Miller, No. 1,711,361, dated April 30, 1929.

Arranged to supply the siruping machine with sirup is a storage tank 6 communicating with the siruper 1 through the medium of the feed pipe 7. A control valve 8 is placed in this pipe for controlling the flow of sirup from the tank 6 into the siruper. This tank is supplied with sirup from a suitable source of supply through the inlet pipe 9 having a control valve 10 therein. The tank, at its upper end, is provided with a hollow

preferably cone-shaped baffle 11, having a water chamber 12 into which water is admitted from a cold water supply by pipe 13 having a control valve 14. An overflow 15 for the chamber communicates with an overflow pipe 16 having a control valve 17. This baffle is arranged beneath a delivery nozzle 18 extending through the top of the tank and connected by a pipe 19 with a circulating pump 20 which, in turn, is connected with the delivery pipe 7, above the valve 8, by a pipe 21. A valve 22 is arranged within the pipe 21 for controlling the flow of sirup to the circulating pump 20.

The tank 6 is sealed against the ingress of air by the sealing cover 23 and is connected by 15 the pipe 24 with a vacuum pump 25. The top of this tank is also connected through a pipe 26 with a source of supply of carbon dioxide 27 and arranged in this conduit 26 is a control valve 28. The source of supply 27 of the carbon dioxide is also connected through the medium of the pipe 29 with the top of the siruping tank through a water sealed coupling 30, a suitable valve 31 being placed in this pipe for controlling the flow of carbon dioxide to the tank. This 25 valve, as well as the valve 28, may be of the reducing type to control not only the admission of carbon dioxide to the different tanks but also to regulate the pressure thereof.

In operation, the sirup is flowed into the tank 30 6 from the supply pipe 9 until the tank has received the desired quantity. Preferably, the level of the sirup is maintained at or is not permitted to rise above the point 32 as indicated in the drawing. After the sirup has been admitted into the tank, the supply pipe valve is shut off and by opening the valve 22 and operating the circulating pump 20, the sirup is removed from the bottom of the tank and discharged through the top thereof over the baffle 11. This spreads the sirup into a thin film, cooling it at the same time, and with the vacuum producing pump 25 operating, the air from the tank 6 is exhausted; it being understood that the valve 8 is in a closed position. The vacuum producing 45 pump exhausting the air from the tank also exhausts the air from or deaerates the sirup in the tank and this deaerating process is accelerated due to the fact that the syrup is flowing in a thin cooled film over the baffle 11. After the 50 vacuum producing pump has been operated for a sufficient length of time, this pump is stopped and the vacuum in the tank is broken by the admission into the top thereof of a suitable supply of CO₂ under predetermined pressure so that 55

the flow of the sirup will be permitted through the pipe 7. Due to the fact that the vacuum is broken by the admission of CO₂, there will be no danger of the sirup again absorbing air. Furthermore, the tank of the siruper 1 is provided with an atmosphere of CO₂ above the sirup level and this atmosphere is preferable maintained at atmospheric pressure. The pressure of the CO₂ in the tank 6 above the liquid level may also be maintained at atmospheric or slightly above atmospheric pressure so that the sirup will flow freely into the tank when the valve 8 is opened.

I claim as my invention:

An apparatus for deaerating sirup comprising in combination a tank adapted to contain the sirup, a hollow filming plate, arranged in said

tank near the top thereof, means for circulating a cooling medium through said hollow plate, a circulating pump having its intake side connected to the bottom of the tank and its delivery side connected to the top of said tank above said filming plate and adapted to deliver the sirup over said plate into said tank, means for creating a sub-atmospheric pressure in said tank during the circulation of the sirup through said tank for removing the air from said sirup and means for admitting CO₂ to the top of said tank for breaking said sub-atmospheric pressure when it is desired to withdraw the contents of the tank therefrom.
